UNITED STATES PATENT OFFICE.

SAMPSON H. RENVILLE, OF PEEVER, SOUTH DAKOTA.

NECK-YOKE CENTER.

1,015,248.

Specification of Letters Patent.

Patented Jan. 16, 1912.

Application filed December 27, 1910. Serial No. 599,343.

To all whom it may concern:

Be it known that I, SAMPSON H. RENVILLE, a citizen of the United States, residing at Peever, in the county of Roberts and 5 State of South Dakota, have invented certain new and useful Improvements in Neck-Yoke Centers; and I do hereby declare the following to be a full, clear, and exact description of the invention, such as will enable others skilled in the art to which it 10 pertains to make and use the same.

My invention has for its object to provide an improved neck yoke center and to this end it consists of the novel devices and combinations of devices hereinafter described 15 and defined in the claims.

In the accompanying drawings which illustrate the invention, like characters indicate like parts throughout the several views.

20 Referring to the drawings, Figure 1 is a view in rear elevation with some parts broken away and with some parts shown in section; Fig. 2 is a view in vertical section taken on the line $x^2 x^2$ of Fig. 1; Fig. 3 is a 25 detail view in horizontal section taken on the line $x^3 x^3$ of Fig. 1; and Fig. 4 is a detail view of a portion of the so-called clamping band.

The numeral 1 indicates the neck yoke and 30 the numeral 2 the front end portion of a vehicle pole which latter is provided with the customary pole cap 3 having a segmental stop holder 4. The neck yoke center is adapted to be secured to the intermediate 35 portion of the neck yoke 1 by means of a split clamping band 5, the free ends of which are brought together at the underside of the neck yoke 1 and terminate in depending flanges 6 detachably secured together by 40 means of short nutted bolts 7. On the outer face of each flange 6 is detachably secured by means of the nutted bolts 7, a plate 8 having formed therein a half socket 9, and the intermediate portions of the flanges 6 between 45 the half sockets 9 are cut away to form a seat 10. Swiveled within the co-operating half sockets 9 and the seat 10 is a supporting head 11 terminating at its lower end in a depending hinge lug 12. The 50 clamping band 5 is positively held against movement on the neck yoke 1 by means of a wood screw 13 countersunk in the clamping band 5 and screwed into the neck yoke 1. The pole socket is in the form of a metallic 55 disk 14 having a marginal and laterally projecting annular flange 15. At its central

portion, the disk 14 is provided with the customary perforations 16 through which the pole cap 3 is adapted to be inserted. Secured to the upper surface of the flange 15 is a pair of laterally spaced hinged lugs 17 adapted to receive therebetween the hinge lug 12, and the hinged lugs 12 and 17 are secured together for hinge-like movement by means of a long hinge bolt 18 passed through alined perforations formed therein. 60 To prevent accidental removal of the hinge bolt 18, the same is provided with a nut 19 and a cotter 20.

70 Detachably mounted within the annular flange 15 is a non-metallic filling block 21 preferably made up of several thicknesses of leather sewed together and provided with a central perforation 22 which is alined with the perforation 16 in the disk 14 through 75 which the pole cap 3 is adapted to be inserted as far as permitted by the stop flange 4 (see Fig. 2). By reference to Fig. 2, it will be noted that the central perforation 22 of the filling block 21 is of slightly less diameter than the diameter of the perforation 16 in the disk 14 thereby preventing any of the metallic parts of the neck yoke center 80 from coming in contact with the pole cap 3 or the stop flange 4. The filling block 21 is 85 detachably held within the annular flange 15 by means of several small screws 23, as shown, three. By making the non-metallic filling block 21 detachable, the same may be turned into various different positions within 90 the annular flange 14 and when worn out, a new filling block may be substituted therefor.

The numeral 24 indicates a so-called lock yoke, the prongs of which are pivoted on 95 the hinged bolt 18, and the lower portion of which is adapted to be engaged with the pole cap 3, just at the rear of the stop flange 4, so as to thereby hold the pole socket from accidentally slipping off from the pole cap. 100

The swivel connection between the members of the neck yoke center permits free action between the neck yoke and the pole.

What I claim is:

1. In a neck yoke center, the combination 105 with a neck yoke and a clamping band surrounding the same and having formed therein a pair of co-operating head receiving seats, of detachable half-sockets secured to said clamping band for co-operation with 110 said seats, a pole socket having a pole passage, and a connecting head secured to said

pole socket and swiveled in said seats and coöperating half-sockets, substantially as described.

2. In a neck yoke center, the combination
5 with a neck yoke and a clamping band sur-
rounding the same and having formed there-
in a pair of coöperating head receiving seats,
of detachable half-sockets secured to said
clamping band for coöperation with said
10 seats, a pole socket having a pole passage,

and a connecting head secured to said pole
socket by a hinge joint, and swiveled in
said seats, and coöperating half-sockets, sub-
stantially as described.

In testimony whereof I affix signature in 15
presence of two witnesses.

SAMPSON H. RENVILLE.

Witnesses:

A. F. ERTSGAARD,
FLEETA RENVILLE.
